US0D1067600S

(12) **United States Design Patent** (10) Patent No.: **US D1,067,600 S**
(45) Date of Patent: ** Mar. 25, 2025

(54) **FOOTWEAR UPPER**

(71) Applicant: **Wolverine Outdoors, Inc.**, Rockford, MI (US)

(72) Inventor: **Brenton S. Wehrmeyer**, Grand Rapids, MI (US)

(73) Assignee: **Wolverine Outdoors, Inc.**, Rockford, MI (US)

(**) Term: **15 Years**

(21) Appl. No.: **29/889,076**

(22) Filed: **Apr. 7, 2023**

(51) LOC (15) Cl. **02-04**

(52) U.S. Cl.

USPC **D2/969**; D2/923

(58) **Field of Classification Search**

(57) **CLAIM**

The ornamental design for a footwear upper as shown and described.

DESCRIPTION

FIG. 1 is a perspective view of a footwear upper embodying the new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The figures show features in even broken lines that form no part of the claimed design. The dot-dash broken lines depict the bounds of the claim and form no part thereof.

1 Claim, 7 Drawing Sheets
